CURTAIN FABRIC

Harold T. Marshall, Sharon, Mass., assignor to
The Kendall Company, Walpole, Mass., a cor-
poration of Massachusetts

Application November 10, 1937, Serial No. 173,874

2 Claims. (Cl. 28—1)

This invention relates to curtains and curtain fabrics.

A high percentage of the curtains used in the home are made by the housewife. She goes to the store and selects a curtain fabric suited to her requirements. Usually this material is of an open-mesh character which is shipped to the retailer in the form of bolts. That is, the fabric is either rolled or folded to present it in a relatively compact form from which the salesman can draw any suitable length ordinarily required by a customer. He cuts off the length desired by the purchaser and she later cuts this into suitable lengths for individual curtains.

15 In making a curtain it is necessary for her to run a hem along the vertical edge which will hang approximately in front of the center of the window, this hem being required partly to give the edge a better appearance and partly, also, to reduce the tendency of the curtain to sag. Often it is necessary to hem both edges, although with some fabrics the margin which is to be positioned at the side of the window casing is left unhemmed. The making of either type of these hems is a 20 laborious proceeding. It is necessary first to fold over a portion of the margin of the curtain of the width desired for the hem. In order to hold the fold in place, it is necessary to pin it at frequent intervals. Also the width must be measured at 25 the pinned points to make sure that the hem will be even. These folding and pinning operations start at one end of the curtain and proceed to the opposite end. Next, the folded over portion is basted. Subsequently it is pressed or ironed, this 30 step being necessary to make the flimsy curtain material retain the fold. The hem then is ready to be stitched. After this operation has been performed, the basting threads are removed. This process has been followed without any material 35 change for generations.

40 The present invention aims to improve curtain webs and the methods of preparing them for merchandizing with a view to reducing very materially the labor required in performing these hemming operations.

45 I have found that this object can be realized by folding one or both margins of the curtain fabric, as may be desired, in connection with the winding, folding, or other manipulations of the web required in working it into the form of a bolt. The customary method of making a bolt is to 50 unwind the web from a supply roll or beam, feed it through a series of folding fingers and wind it up again on a cloth board or some other suitable 55 form. Or, instead of winding the web, it may be

folded in any one of several well known mechanisms to produce a folded bolt. If desired, in connection with these operations, the web may be cut into specified lengths which may either be worked into a single bolt, or into separate and 5 much smaller bolts. These winding and folding mechanisms are well known, and the manner in which the folding fingers are arranged to produce the doubling and folding is thoroughly understood by those skilled in this art. The only changes required in these machines to produce the results sought by the present invention are to arrange the folding fingers so that the margin or margins, as the case may be, of the web will be folded over in connection with the doubling operation and as the 10 web travels toward the winding mechanism or to the mechanism which folds the web transversely into layers of predetermined dimensions to produce a folded bolt. The line of fold is automatically creased or set by the operation of the 15 machine just at the longitudinal line or crease on which the goods are doubled.

Typical embodiments of the invention are shown in the accompanying drawing, in which

Figure 1 is a perspective view of a bolt of curtain fabric with the web partly unwound, showing a fold which may be used when one vertical margin only of the curtain is to be hemmed; and

Fig. 2 is a similar view illustrating a typical fold which may be used when both vertical margins are to be hemmed.

Referring first to Fig. 1, the web of curtain fabric there shown is folded longitudinally on the line 2 to double it, as is customary in the put-up of fabrics, except those of very narrow widths. 35 Usually the two selvage edges of the fabric are brought together in registered relationship at the opposite edge of the folded web. According to the present invention, however, a marginal portion 3 at one edge of the goods is folded over and is 40 pressed or creased sufficiently along the line of fold 4 to make the goods retain this fold. This turned over margin is made of suitable width for the curtain hem. Preferably the two edges 5 and 6 of the web are disposed substantially in meeting 45 relationship, both lying upon the unfolded bottom layer 1.

In using this material the housewife purchases a length of these goods suited to her requirements and later cuts this into curtain lengths. 50 She can then proceed immediately to stitch the hem or hems, all the preliminary operations which have heretofore been required having been eliminated by the fact that the fabric comes to her all folded and ready to stitch. She simply 55

runs a seam through the margin of the folded portion at a suitable distance from the edge 5. If she wishes, she can turn the selvage 8 under, she can cut it off, or she can stitch it on flat. 5
5 But in any event, the preparatory operations which it has been necessary for her to perform heretofore, including folding, measuring, pinning and basting, ironing or pressing the crease, and finally removing the basting threads, are obviated. 10 In addition, she is assured an even hem for the reason that the hem has been folded in a machine operation which performs this step with a degree of accuracy that is hard to equal by hand. Thus she produces a finished product 15 having a better appearance with materially less labor. In this connection it may be pointed out that if the hems at the center of the window are uneven or irregular, that fact detracts greatly from the appearance of the curtains and the 20 window, since these hems are at a point where any faults in their construction are very conspicuous.

If the goods are of such a nature that both 25 margins are to be hemmed, the folding and creasing operations may be performed in the manner above described except that both margins are folded and creased, as shown in Fig. 2. The margin 3 is folded outwardly, as in Fig. 1, while the opposite margin 9 is folded inwardly or under, 30 so that when the web is opened both folds lie on the same side of the goods.

Essentially the same idea is also applicable to some other goods, particularly drapery materials, and accordingly, the term "curtain fabrics" is 35 here used in a generic sense to include other goods to which the invention is applicable. In addition to facilitating the manufacture 40 of curtains in the home, the invention can also be used advantageously in the commercial manufacture of these products. That is, the curtain

manufacturers purchase their curtain fabrics in bolts in which, however, the cloth usually is not doubled. The webs in these bolts, however, may have their margins folded in the same manner above described, thus saving the operations of subsequently folding the goods preparatory to sewing the hems. This results in a saving to the manufacturer since the expense of putting up the goods in this manner in the textile mill or the finishing plant does not add materially to the expense of manufacture at this point. 10

Having thus described my invention, what I desire to claim as new is:

1. A cloth bolt consisting essentially of a web of curtain fabric from which lengths may be 15 cut off suited to the requirements of individual purchasers, the opposite longitudinal marginal portions of said web being folded over and creased at the lines of fold, said folded over portions each being of suitable width for a hem designed 20 to extend along a vertical edge of the curtain, said web being doubled longitudinally and one of said margins being folded outwardly and the other inwardly whereby both folded over margins, when the web is opened, will lie upon the 25 same side of the goods.

2. A cloth bolt consisting essentially of a web of curtain fabric from which lengths may be cut off suited to the requirements of individual purchasers, said web including a longitudinal marginal portion of a width less than one-half the width of said bolt, folded over and creased at the line of fold and said portion being of approximately the proper width for a hem designed to extend along the vertical edge of the curtain, the 30 edge of said folded over margin approximately meeting the opposite edge of the web and both lying upon an unfolded layer of the web extending the length of the web.

HAROLD T. MARSHALL. 40
